(57) **CLAIM**

The ornamental design for a suction mount as shown and
described.

DESCRIPTION

FIG. 1 is an upper perspective view of a suction mount in
accordance with a first embodiment of my new design;
FIG. 2 is a front elevation view of the suction mount of FIG.
1;

FIG. 3 is a rear elevation view of the suction mount of FIG.
1;

FIG. 4 is a left side elevation view of the suction mount of
FIG. 1;

FIG. 5 is a right side elevation view of the suction mount of
FIG. 1;

FIG. 6 is a top plan view of the suction mount of FIG. 1;
FIG. 7 is a bottom plan view of the suction mount of FIG.
1;

FIG. 8 is an upper perspective view of a suction mount in
accordance with a second embodiment of my new design;

FIG. 9 is a front elevation view of the suction mount of FIG.
8;

FIG. 10 is a rear elevation view of the suction mount of FIG.
8;

FIG. 11 is a left side elevation view of the suction mount of
FIG. 8;

FIG. 12 is a right side elevation view of the suction mount of
FIG. 8;

FIG. 13 is a top plan view of the suction mount of FIG. 8;
and,

FIG. 14 is a bottom plan view of the suction mount of FIG.
8.

The broken lines depict portions of the suction mount that
form no part of the claimed design.
